UNITED STATES PATENT OFFICE

ARTHUR ATWATER KENT, OF ARDMORE, PENNSYLVANIA

DESIGN FOR A CABINET FOR RADIO RECEIVING APPARATUS

Application filed May 26, 1930. Serial No. 35,765. Term of patent 7 years.

To all whom it may concern:

Be it known that I, ARTHUR ATWATER KENT, a citizen of the United States, residing at Ardmore, county of Montgomery, State of Pennsylvania, have invented a new, original, and ornamental Design for a Cabinet for Radio Receiving Apparatus, of which the following is a specification, reference being had to the accompanying drawing, forming part hereof.

The figure is a perspective view of a cabinet for radio receiving apparatus, showing my new design. The front of the cabinet according to my new design primarily comprises, in combination, a transverse scroll apron located at the base, vertical side panels and an inset central panel rising directly from the scroll apron, a transverse panel above and

extending completely across said side and central panels and arched above the central panel, relatively narrow transverse beading at the junction of the side panels and transverse panels, a relatively wide band provided with vertical ribs and grooves and arranged across the central panel and below the arch and extending below said beading and the upper ends of the side panel, and ornamental beading on the side panels extending above the lower portion of said relatively wide band.

I claim:

The ornamental design for a cabinet for radio receiving apparatus, as shown and described.

ARTHUR ATWATER KENT.
